UNITED STATES PATENT OFFICE.

WILLIAM E. LOVER, OF FINDLAY, OHIO.

COMBINED ENVELOP AND DRINKING-CUP.

1,364,999.

Specification of Letters Patent. Patented Jan. 11, 1921.

Application filed July 2, 1918. Serial No. 243,038.

To all whom it may concern:

Be it known that I, WILLIAM E. LOVER, a citizen of the United States, residing at Findlay, in the county of Hancock and State of Ohio, have invented certain new and useful Improvements in Combined Envelops and Drinking-Cups, of which the following is a specification.

This invention has as its object to provide an advertising novelty in the nature of a combined envelop and drinking cup, the article being so constructed that it may be employed first as an envelop for the transmittal of advertising matter or a business letter and may be subsequently employed by the recipient as a drinking cup.

Another object of the invention is to so construct the article that it may be repeatedly employed as a drinking cup so that the advertising matter which it bears will be more or less constantly brought to the attention of the user.

Another object of the invention is to provide the article with means whereby the mouth of the cup may be effectually protected from being soiled in the transmittal of the article through the mails, the protecting means being of such nature that even though the contents of the envelop be inspected by the postal authorities, the mouth of the cup will not be likely to become fouled.

A further object of the invention is to so construct the article that the mouth of the cup will not only be protected in the first instance in transmittal of the same through the mails, but also in the subsequent use of the article as a drinking cup solely so that, without likelihood of soiling the mouth of the cup the article may be carried in ones pocket, or in a note book, bill book or the like.

In the accompanying drawings:

Figure 1 is a perspective view of the article embodying the present invention looking at the reverse side thereof;

Fig. 2 is a similar view looking at the face side thereof;

Fig. 3 is a vertical sectional view on the line 3—3 of Fig. 1;

Fig. 4 is a horizontal sectional view on the line 4—4 of Fig. 1;

Fig. 5 is a plan view of the blank.

The article embodying the present invention is so formed that it may be cut from a single integral sheet of paper and then folded in a simple and convenient manner to form the envelop and the cup inclosed thereby. The article comprises essentially an envelop portion indicated in general by the reference letter A and a cup portion indicated by the reference letter B. Of the envelop portion, the numeral 1 indicates the front and the numeral 2 the back, these portions being of the usual rectangular outline and of any desired size. Integral with one end edge of the front 1 is a permanent closure flap indicated by the numeral 3, this flap being gummed upon its inner face as indicated by the numeral 4, so that when the back 2 is folded over to confront the front 1, the said flap 3 may be folded down upon the outer face of the said back 2 and secured by the adhesive. The said front 1 is provided at its opposite end edge with an integral closure flap 5 having a locking tongue 6 of any suitable contour, and the back 2 is formed with a slit 7 into which the locking tongue 6 may be inserted for the purpose of securing the closure flap 5 in position closing the mouth of the envelop. As will be presently explained, the closure flap 5 serves also as a protecting and closing flap for the mouth of the drinking cup in the completed condition of the article. The numeral 8 indicates a temporary protecting flap which is integral with that end edge of the back 2 corresponding to the edge with which the flap 5 is integral.

The cup portion of the article includes a side 9 and a side 10 and the latter side is provided at its outer longitudinal edge with an integral flap 11 one face of which is provided with an adhesive coating indicated by the numeral 12. Also the inner face of the side 9 at that end corresponding to the end of the front 1 of the envelop portion with which the flap 3 is connected, is provided with a narrow area of adhesive indicated by the numeral 13.

In folding up the blank from which the article is to be formed, the said blank is folded along the line of juncture of the front 1 of the envelop portion with the side

9 of the cup portion and said cup portion is folded along the line of juncture of its sides 9 and 10 and also along the juncture of the flap 11 with the said side 10. The 5 gummed side 12 of the said flap 11 is then caused to adhere to the inner face of the side 9 of the said cup portion and the adhesive area 13 is caused to adhere to the inner face of the said side 10, thus forming a cup 10 the mouth of which is indicated by the numeral 14. After having thus formed the cup portion of the article, the said cup portion is folded bodily to lie against the inner face of the front 1 of the envelop, after 15 which the back 2 of the envelop portion is folded over and secured by its adhesive coating indicated by the numeral 15, to the outer face of the side 9 of the said cup portion. Finally the flap 3 is folded over 20 and its adhesive bearing side is secured to the outer face of the back 2 of the envelop portion.

By reference to the drawings it will be observed that the adhesive coating 15 extends substantially over the entire area of the inner face of the back 2 of the envelop portion except that in an area, indicated by the numeral 16, in which the slit 7 is located, the adhesive coating is not applied 25 so that a pocket is formed between the said back 2 of the envelop portion and the side 9 of the cup portion in which the locking tongue 6 of the flap 5 may be received.

Having folded up the article in the manner stated above, the flap 8 is to be folded inwardly over the mouth of the cup so as to effectually close and protect the said cup. The article is then in condition to receive the mail matter to be transmitted, and such 30 matter is, of course, inserted between the side 10 of the cup portion and the front 1 of the envelop portion. After the matter to be transmitted has been placed within the article, the closure flap 5 is to be folded 45 over and secured by the insertion of the locking tongue 6 through the slit 7.

After the article has served its purpose as a mailing envelop the recipient will tear off the flap 8 which, in the transmittal of 50 the article through the mails, has protected the mouth of the drinking cup. Then the article may be employed as an ordinary paper drinking cup and after use the closure flap 5 may be turned down and locked 55 in place so as to effectually protect the mouth of the cup. Of course, the sides 9 and 10 of the cup will be suitably water-proofed, as for example, by a coating of paraffin.

It is preferable that the locking tongue 60 6 be of the shape shown in the drawings, the said tongue comprising a relatively wide body portion 17 having rounded margins 18, and a relatively narrow neck 19. This tongue is bifurcated or formed with a slit 65 20 extending inwardly from its outer edge

and to or slightly inwardly beyond the neck 19, as clearly shown in Fig. 5. The slit 7 which receives the tongue is preferably of a length substantially equal to the width of the neck 19 and consequently of a length less 70 than the maximum width of the body portion 17 of the tongue and therefore when inserting the tongue through the slit it is only necessary to move together the portions provided by the formation of the slit 75 20 so that they will slightly overlap and thus the width of the body portion of the tongue will be reduced to permit of its being inserted through the said slit 7. Of course, after the tongue has been so inserted that 80 the neck 19 is within the slit 7, the tongue will expand and will be effectually locked against withdrawal until the portions are again moved together as the tongue is being withdrawn.

It is preferable that the front of the article be provided with a transparent area or window 21 which may extend over a part or the entire area of the said front and through which the name and address of the 90 addressee may be visible, or, where the entire surface is transparent, not only will the name and address be visible, but the letter head will also be visible and may therefore serve the purpose of the usual return card.

Having thus described the invention, what is claimed as new is:

An article of the class described formed from a single integral blank comprising an 100 envelop wall, a water-proofed wall connected by a line of fold therewith, a second water-proofed wall connected by a line of fold with the first mentioned water-proofed wall, a flap connected by a line of fold 105 with the last mentioned wall at its free longitudinal edge and extending throughout substantially the length thereof, the said water-proofed walls being folded together and the said flap being secured to the inner 110 face of the first mentioned one of said walls, the said water-proofed walls being folded with relation to the envelop portion so that the second mentioned water-proofed wall will lie against the inner face of the said envelop portion, the envelop portion being provided at its upper edge with a closure flap and at its lower edge with a sealing flap, a fourth wall integral with the other longitudinal edge of the envelop wall and folded to lie against the outer face of the first mentioned water-proofed wall and having adhesive applied to the entire area of its said face except for a definite portion near the top thereof whereby it is united to 115 the said first mentioned water-proofed wall except for the said area and thereby provide a pocket, the sealing flap being folded to lie against and being secured to the outer face of the last mentioned wall and the said last 120 125 130

mentioned wall at its upper edge being provided with a closure flap insertible between the envelop wall and the adjacent water-proofed walls, and the closure flap of the envelop wall being foldable to overlie the upper ends of all of the walls and having

a tongue insertible through a slit formed in that portion of the fourth mentioned wall within the bounds of the area to which adhesive is not applied.

10

In testimony whereof I affix my signature.
WILLIAM E. LOVER. [L. s.]
